HATCH FRAME CONSTRUCTION FOR CAR ROOFS

David W. Hawksworth, Birmingham, Mich., assignor to Chicago-Hutchins Corporation, Chicago, Ill., a corporation of Delaware

Application May 4, 1936, Serial No. 77,877

6 Claims. (Cl. 108—5.4)

The invention relates to car roofs provided with hatch openings therein and has for its object the obtaining of an improved construction of hatch with more particular reference to the frame thereof and the means for forming a weather-proof joint between said frame and the roof permitting of independent movement thereof.

In the present state of the art, certain cars and particularly refrigerator cars are provided with hatch openings in the roof through which the ice or refrigerating material is introduced. The hatch opening is protected by a frame which forms a tapering liner therefor adapted to receive the closure plug and which at its upper end must form a weather-proof joint with the roof sheeting. It is necessary that this frame should be securely fastened, as otherwise the jolting of the car may displace the same thereby destroying the seal and otherwise damaging the construction. It is also necessary to provide for a limited independent movement of the roofing sheets with reference to said frame so as not to interfere with the flexibility of the roof to compensate for weaving or other distortion in the roof frame. It is further desirable to have a construction which can be easily assembled with the car roof. My invention, therefore, consists in an improved construction through which the conditions above described are fulfilled as hereinafter described.

In the drawings:

Figure 1 is a plan view of a portion of a car roof having my improved construction of hatch therein;

Figure 2 is a transverse section on line 2—2 of Figure 1;

Figure 3 is a longitudinal section on line 3—3 of Figure 1;

Figure 4 is a sectional perspective view of a portion of the hatch frame;

Figure 5 is a similar view of a portion of the roofing sheet with which the frame is engaged;

Figure 6 is a section on line 6—6 of Figure 2.

Refrigerator cars are usually provided with an outer roof and an inner ceiling between which members is arranged heat insulating material. The hatch opening extends through both the roof and the ceiling and, as above stated, is provided with a liner frame. As specifically shown, A is the outer roof; B the ceiling and C the insulating material. D is the hatch opening which is between transversely extending members E and E' forming a portion of the ceiling and roof frame. F and F' are longitudinally extending members which form the other sides of the hatch opening

and the upper faces of which conform to the pitch of the roof.

The outer roof is formed by metallic roofing sheets resting upon the roof frame, and the roofing sheet A' which covers the portion of the frame in which the hatch opening is located, is provided with a corresponding opening therein. The metal of the sheet surrounding this opening is pressed upward to form an obliquely extending raised ledge G terminating in an upwardly extending flange G'. These portions are continuous around the opening, while the opening within the flange G' is somewhat greater in dimension than the opening between the members E, E' and F, F'. I is a hatch frame having tapering side walls I' which fit within the hatch opening against the members E, E' and F, F'. The upper portion of this frame extends above the level of the roof and is provided with a laterally extending flange I², a downwardly extending flange I³ and an obliquely and outwardly extending flange I⁴ adapted to rest upon the oblique flange G of the roofing sheet A'. To facilitate manufacture, the portions I³ and I⁴ may be separately formed from the portions I' and I², and the portion I³ is provided with a laterally extending portion I⁵ which overlaps the portion I² and is secured thereto, preferably by welding. The portion I³ is also spaced from the upstanding flange G' on the roofing sheet so as to permit lateral movement of the latter without interference.

To hold the frame I in position so that it cannot be displaced by the jolting of the car, it is provided with securing brackets J which are attached thereto, preferably by welding. These brackets have a portion J' fitting against the portion I' of the frame, a flange J² fitting beneath the portion I² and the outwardly extending lower flange J³ which is bifurcated to receive a securing bolt K. There are preferably four of the brackets J secured on opposite sides of the frame and the bolts K extend downward through apertures in the members E and E', as shown in Figure 3. The upper head K' of each bolt is secured from turning by a locking member L which is also preferably welded to the member J. This locking member has a portion L' extending outward spaced from the flange J³ and at its outer end a portion L² which can be turned down to lock the head from disengagement.

With the construction above described, after the roofing sheet A' is placed in position the hatch frame I is inserted in the hatch opening. Before doing this the bolts K are engaged with the brackets J and the heads K' of these bolts are

50

55

locked by bending down the outer portions L² of the locking member L. The bolts are then threaded through bores in the members E and E' and the frame I lowered to rest the flanges I⁴ upon the obliquely extending portions G of the roofing sheet. The frame is then clamped down by tightening the nuts K³ which engage threaded ends of the bolts K thereby tightly pressing the flanges I⁴ against the portions G to make a weather-proof joint. Nevertheless, these portions are permitted to move laterally with respect to each other, as necessitated by the flexing of the roof.

The hatch is provided with the usual closure plug M and hatch cover N. These are provided with hinges O and P which are pivotally attached to a bracket Q on an angle bar R which extends transversely of the roof and are suitably anchored thereto. A specific construction of these members is not, however, a part of the present invention.

What I claim as my invention is:

1. In a car roof having a hatch opening therein, a roofing sheet having a registering opening of larger dimensions and provided with an upwardly extending continuous annular flange surrounding said opening, a metallic hatch frame having a depending portion extending within said hatch opening and a portion extending upward above said annular flange and then outward and downward to continuously surround said flange and bear upon said roofing sheet below said flange with a clearance between the same and said flange, and securing means for holding said metallic frame down upon said roofing sheet to form a weather-proof joint while permitting independent movement of said sheet.

2. In a car roof having a hatch opening therein, a roofing sheet having a registering opening of larger dimensions and provided with an upwardly extending continuous annular flange surrounding said opening, a metallic hatch frame having a depending portion within said hatch opening and a portion extending upward above said annular flange and then outward and downward to continuously surround said flange and bear upon said roofing sheet below said flange with a clearance between the same and said flange, and securing means engaging said metallic frame between the inner and outer portions thereof for holding said frame down upon the roof and for forming a weatherproof joint between said frame and roofing sheet permitting independent movement of the latter.

3. In a car roof having a hatch opening therein, a roofing sheet having a registering opening of larger dimensions with a raised portion surrounding said opening and provided with an upwardly extending continuous annular flange at its inner edge, a metallic hatch frame provided with a depending portion fitting within said hatch opening and a portion extending upwardly above said flange then outward and downward to continuously surround said flange with a clearance between the same and said flange, said downward portion terminating in a laterally outwardly extending foot portion resting upon the raised portion of said sheet below

said flange, and securing means engaging said metallic frame between the outer and inner portions thereof for holding said frame down upon the roof and pressing said foot portion against the raised portion of said sheet to form a weatherproof joint while permitting independent movement of the sheet.

4. In a car roof, the combination with a roof frame having longitudinally and latitudinally extending members surrounding a hatch opening, of a roofing sheet supported on said frame and having a registering opening of larger dimensions with an upwardly extending continuous annular flange surrounding said opening, a metallic hatch frame having a depending portion within said hatch opening seated against said longitudinally and latitudinally extending members, said frame also extending upward above said annular flange then outward and downward to continuously surround said flange with a clearance between the same and said flange, said downward portion terminating in a foot flange for resting upon said sheet below said flange, brackets secured to said hatch frame outside the depending portion thereof, and bolts engaging said brackets extending downward through said roof frame whereby said metallic frame is held down upon the roof with a weather-proof joint between said foot flange and roofing sheet permitting independent movement of the latter.

5. In a car roof having a frame provided with a hatch opening therein, of a roofing sheet supported on said frame having a registering opening of larger dimensions and provided with an upwardly extending annular flange continuously surrounding said opening, a pressed sheet metal hatch frame having a depending portion engaging said hatch opening and a portion extending upward above said annular flange then outward and downward to rest upon said sheet below said flange, with a clearance between the same and said flange, said metallic frame having brackets welded thereto outside said depending portion and having clearance inside said flange, and bolts having the heads thereof engaging said brackets, said bolts passing downward through said roof frame and being secured on the inner side thereof.

6. In a car roof, the combination with a roof frame having a hatch opening therein, of a metallic hatch frame comprising a member having a downwardly tapering portion with a laterally outwardly extending flange at its upper end, a second member having a laterally inwardly extending flange welded to said laterally outwardly extending flange of the first member, said second member having a downwardly extending annular outer portion terminating in a laterally extending foot flange, brackets having a securing portion beneath and extending downward from said laterally outwardly extending flange welded to the outer face of said first member and arranged between the same and the downwardly extending portion of said second member, and bolts engaging said brackets for securing said metallic frame down upon said roof frame.

DAVID W. HAWKSWORTH.
